(57) **ABSTRACT**

A scraping apparatus, including: a gripping assembly, for gripping a stick of a cleaning tool; a bar, extending from the gripping assembly, the bar shaped to include a first section being adjacent and parallel to the broom stick, and a second section being adjacent and parallel to a brush of the broom; a scraping tip disposed at an end of the bar; and a location disposition mechanism, for manually allowing sliding the bar in relation to the broom stick and for manually disallowing the sliding against pressure applied on the scraping tip.

**CROSS-REFERENCE TO RELATED
APPLICATIONS**

This application claims the benefit of priority from U.S. Provisional Application No. 62/638,161, filed Mar. 4, 2018, the disclosure of which is incorporated herein by reference.

TECHNICAL FIELD

The invention relates to the field of household cleaning. More particularly, the invention relates to an apparatus for accompanying a broom.

BACKGROUND

There are many different types of brooms available for cleaning floors. Most have a relatively soft brush which frequently cannot remove debris which is stuck to the floor while sweeping. A scraper must then be used to loosen the debris from the floor prior to sweeping.

Connecting a scraping element requires significant force of holding together with providing friendly moving of the scraping element.

The purpose of the present invention is to provide a solution to the abovementioned problems.

SUMMARY

A scraping apparatus, including:
a gripping assembly;
a bar, extending from the gripping assembly;
a scraping tip; and
a location disposition mechanism.

BRIEF DESCRIPTION OF THE DRAWINGS

Embodiments, features, and aspects of the invention are described herein in conjunction with the following drawings:

FIG. 1 is a side view of a scraping apparatus according to one embodiment of the invention.

FIG. 2 is a side view of the scraping apparatus of FIG. 1, being connected to a broom.

FIG. 3 is a front view of FIG. 2.

FIG. 4 is the side view of FIG. 2 upon lifting the scraping tip.

FIG. 5 is front view of FIG. 4.

FIG. 6 is a top view of disposition mechanism according to another embodiment, being connected to the broom of FIG. 2.

FIG. 7 is a side view of the scraping apparatus of FIG. 1 having the disposition mechanism of FIG. 4, being connected to the broom of FIG. 2.

The drawings are not necessarily drawn to scale.

DETAILED DESCRIPTION

The invention will be understood from the following detailed description of embodiments of the invention, which are meant to be descriptive and not limiting. For the sake of brevity, some well-known features are not described in detail.

The reference numbers have been used to point out elements in the embodiments described and illustrated herein, in order to facilitate the understanding of the inven-

2
tion. They are meant to be merely illustrative, and not limiting. Also, the foregoing embodiments of the invention have been described and illustrated in conjunction with systems and methods thereof, which are meant to be merely illustrative, and not limiting.

FIG. 1 is a side view of a scraping apparatus according to one embodiment of the invention.

A scraping apparatus **10** according to one embodiment of the invention, includes a hollow cylinder **14**, for gripping a broom stick (not shown); a bar **18**, extending from hollow cylinder **14**, and being slideable in relation to the broom stick; and a scraping tip **50**, extending from bar **18**.

FIG. 2 is a side view of the scraping apparatus of FIG. 1, being connected to a broom.

15 The term "broom stick" refers herein as well to a squeegee stick, or to any stick of a cleaning tool.

Bar **18** includes a straight section **52A**, for being disposed near and parallel to the broom's stick **12**; and a rounded section **52B**, for being disposed near and parallel to the broom's brush.

Scraping apparatus **10** further includes at least one location disposition mechanism, for ascending and descending bar **18** in relation to broom stick **12**.

A location disposition mechanism **56A** constitutes a screw **16**, for thrusting broom stick **12**.

A location disposition mechanism **56B** constitutes a hole **20**, for housing a bolt **22**, being pressed by a horizontal spring **24** at a low disposition of bar **18** against a vertical spring **26**.

30 FIG. 3 is a front view of FIG. 2.

FIG. 4 is the side view of FIG. 2 upon lifting the scraping tip.

Upon pressing bolt **22**, spring **26** lifts bar **18**.

FIG. 5 is front view of FIG. 4.

35 FIG. 6 is a top view of disposition mechanism according to another embodiment, being connected to the broom of FIG. 2.

A location disposition mechanism **56C** includes an external hollow cylinder **30A**, functioning as a cart as including wheels **32**, for allowing free sliding **66** of hollow cylinder **14** along broom stick **12**; and an internal hollow cylinder **30B**, being pivotally connected by a hinge **36** to external cylinder **30A**.

Thus internal hollow cylinder **30B** is tiltable (not shown in FIG. 4) in relation to external hollow cylinder **30A**.

FIG. 7 is a side view of the scraping apparatus of FIG. 1 having the disposition mechanism of FIG. 4, being connected to the broom of FIG. 2.

Location disposition mechanism **56C** further includes a spring **38** for normally tilting, as shown by arrow **68**, internal cylinder **30B**, as shown in FIG. 5. The internal side of internal cylinder **30B** includes insoles **58**, for producing friction force with broom stick **12**.

Bar **18** is pivotally connected by a hinge **64A** to internal cylinder **30B** and extends therefrom. Thus, upon scraping, bar **18** is lifted by the floor, and the lifting is converted to rotate internal cylinder **30B**, thus increasing the friction pressure of insole **58** on broom stick **12**.

Moving scraping tip **50** is enabled by pressing a handle **40** of internal cylinder **30B** against spring **38**, being downwards in the example of FIG. 4, and then the user may freely slide external cylinder **30A** in relation to broom stick **12**.

External cylinder **30A** is intended to be surrounded by four fingers **62A** and the hand **62B**; and handle **40** is intended to be pressed by the thumb **62C**.

Thus, in one aspect, the invention is directed to a scraping apparatus (**10**), including:

a gripping assembly (14), for gripping a stick (12) of a cleaning tool;
 a bar (18), extending from the gripping assembly (14), the bar shaped to include a first section (52A) being adjacent and parallel to the broom stick (12), and a second section (52B) being adjacent and parallel to a brush (54) of the broom;
 a scraping tip (50) disposed at an end of the bar (18); and a location disposition mechanism (56A,56B,56C), for manually allowing sliding the bar (18) in relation to the broom stick (12) and for manually disallowing the sliding against pressure (60) applied on the scraping tip (50).

The gripping assembly (14) may include:

a first hollow cylinder (30A), allowing free sliding of the external hollow cylinder (30A) in relation to the broom stick (12); and

a second hollow cylinder (30B), disposed within the first hollow cylinder (30A) and pivotally connected (36) thereto, thereby being tiltable (68) in relation thereto, wherein the bar (18) extends (64A) from the second hollow cylinder (30B),

thereby scraping by the scraping tip (50) presses (60) the bar (18) to tilt (68) the second hollow cylinder (30B) to attach to the broom stick (12), thereby producing friction force therebetween against the free sliding therebetween, thereby providing the disallowing of the sliding of the bar (18) in relation to the broom stick (12) against the pressure (60).

The gripping assembly (14) may further include:

a spring (38), for normally tilting the second hollow cylinder (30B) in relation to the first hollow cylinder (30A), thereby normally producing the friction force between the second hollow cylinder (30B) and the broom stick (12).

The gripping assembly (14) may further include:

a handle (40) for pressing thereof against the spring (38), for cancelling the normal tilting of the second hollow cylinder (30B), thereby allowing canceling the friction force between the second hollow cylinder (30B) and the broom stick (12), for providing the free sliding therebetween.

The second hollow cylinder (30B) may include an insole (58), for producing the friction force.

The second hollow cylinder (30B) may include wheels (32), for providing the free sliding of the external hollow cylinder (30A) in relation to the broom stick (12).

The extension of the bar (18) from the second hollow cylinder (30B) may constitute a pivotal connection thereto applied by a first hinge (64A),

thereby providing the tilt (68) of the second hollow cylinder (30B) by the pressing (60) of the bar (18).

The bar (18) may include a second hinge (64B), for compensating over rotation provided by the first hinge (64A).

In the figures and/or description herein, the following reference numerals (Reference Signs List) have been mentioned:

numerical 10 denotes the scraping apparatus according to one embodiment of the invention;
 12: broom stick;
 14: gripping assembly;
 16: screw;
 18: bar, for physically communicating scraping tip 50 to gripping assembly 14;
 20: hole for housing bolt 22;
 22: bolt;

24: horizontal spring;
 26: vertical spring;
 28: rail;
 30A: external hollowed cylinder;
 30B: internal hollowed cylinder;
 32: wheel/bearing;
 36: horizontal hinge;
 38: vertical spring;
 50: scraping tip;
 52A,52B: sections of bar 18;
 54: brush or squeegee;
 56A,56B,56C: location disposition mechanisms, for allowing the user to vertically locate scraping tip 18;
 58: insole;
 60: pressure applied by scraping tip 50;

62A: fingers;
 62B: hand;
 62C: thumb;
 64A,64B: hinges;
 66: manual vertical sliding, being enabled by pressing handle 40 or by pressing bolt 22;
 68: tilting;
 70: wall for limiting rotation provided by hinge 64B between sections of bar 18.

The foregoing description and illustrations of the embodiments of the invention have been presented for the purpose of illustration, and are not intended to be exhaustive or to limit the invention to the above description in any form.

Any term that has been defined above and used in the claims, should to be interpreted according to this definition.

The reference numbers in the claims are not a part of the claims, but rather used for facilitating the reading thereof. These reference numbers should not be interpreted as limiting the claims in any form.

What is claimed is:

1. A scraping apparatus, comprising:
 a gripping assembly, for gripping a stick of a cleaning tool;
 a bar, extending from said gripping assembly, said bar shaped to comprise
 a first section being adjacent and parallel to said stick, a second section being adjacent and parallel to a brush of the cleaning tool extending outwards from said stick, said second section lacking any element disposed between said second section and said stick, a scraping tip disposed at said end of said bar, thereby said scraping tip is disposed aside said stick and said brush, and
 a third section being tilted in relation to said first and second sections and extending therebetween; and
 a location disposition mechanism, for manually allowing sliding said bar in relation to said stick and for manually disallowing said sliding against pressure applied on said scraping tip, wherein said gripping assembly comprises
 a first hollow cylinder, allowing free sliding of said external hollow cylinder in relation to said stick, and a second hollow cylinder, disposed within said first hollow cylinder and pivotally connected thereto, thereby being tiltable in relation thereto, wherein said bar extends from said second hollow cylinder, thereby scraping by said scraping tip presses said bar to tilt said second hollow cylinder to attach to said stick, thereby producing friction force therebetween against said free sliding therebetween,

thereby disallowing said sliding of said bar in relation to said stick against pressure applied on said scraping tip.

2. The scraping apparatus according to claim 1, wherein said gripping assembly further comprises:

a spring, for normally tilting said second hollow cylinder 5 in relation to said first hollow cylinder, thereby normally producing said friction force between said second hollow cylinder and said stick.

3. The scraping apparatus according to claim 2, wherein said gripping assembly further comprises: 10

a handle for pressing thereof against said spring, for cancelling said normal tilting of said second hollow cylinder, thereby allowing canceling said friction force between said second hollow cylinder and said stick, for providing said free sliding therebetween. 15

4. The scraping apparatus according to claim 1, wherein said second hollow cylinder comprises an insole, for producing said friction force.

5. The scraping apparatus according to claim 1, wherein said second hollow cylinder comprises wheels, for providing 20 said free sliding of said external hollow cylinder in relation to said stick.

6. The scraping apparatus according to claim 1, wherein said extension of said bar from said second hollow cylinder comprises a pivotal connection therebetween applied by a 25 first hinge, thereby said pivotal connection tilts said second hollow cylinder to attach to said stick.

7. The scraping apparatus according to claim 6, wherein said bar comprises a second hinge, for compensating over rotation provided by said first hinge. 30
